(57) **CLAIM**

The ornamental design for a surgical clamp handle, as shown and described.

DESCRIPTION

FIG. 1 is a perspective view of a surgical clamp handle showing our new design, with the handle in a tightened orientation;

FIG. 2 is a front view thereof;

FIG. 3 is a rear view thereof;

FIG. 4 is a top plan view thereof;

FIG. 5 is a left side elevational view thereof;

FIG. 6 is a bottom plan view thereof;

FIG. 7 is a right side elevational thereof; and,

FIG. 8 is a right side elevational thereof, with the handle in a loosened orientation.

The broken line showing of environment is for illustrative purposes only and forms no part of the claimed design.
